J. B. SINGER ET AL
FOLDING DISPLAY DEVICE

Filed April 1, 1921

UNITED STATES PATENT OFFICE.

JOSEPH B. SINGER AND ARTHUR B. LEVY, OF NEW YORK, N. Y.

FOLDING DISPLAY DEVICE.

Application filed April 1, 1921. Serial No. 457,662.

To all whom it may concern:

Be it known that we, JOSEPH B. SINGER and ARTHUR B. LEVY, citizens of the United States, and residents of the city of New York, county and State of New York, have invented certain new and useful Improvements in Folding Display Devices, of which the following is a specification.

The present invention relates to folding display devices of the type shown in Letters Patent of the United States, No. 1,210,008, granted to us December 26th, 1916.

The general object of the present invention is to simplify the construction and reduce the cost of manufacture of the type of display box above referred to, and, at the same time, to increase the effective display surface without appreciably adding to the bulk or area heretofore had by the box when in folded or knockdown position.

To these ends the invention resides in the employment of an intermediate section and interposing said intermediate section between side or wing sections, and providing a connection therebetween for adapting two of said sections to fold upon each other or upon the intermediate section; forming the said panel, the wing or side and the intermediate sections from a single blank of relatively thin or light-weight fibrous stock material, such as pasteboard, and utilizing the supporting properties which each section provides for the other to give the required stability to the relatively thin and flexible body while the box is in display position.

Other objects will appear and be better understood from that embodiment of the invention, of which the following is a specification, reference being had to the accompanying drawings forming part thereof and in which:

Figure 1 is a plan view of a blank forming one embodiment of the invention.

Figure 2 is a perspective of the box in folded and set-up positions and formed from the blank shown in Figure 1.

Figure 3 is a transverse section on the line 3—3 of Figure 2.

Figure 4 is a front elevation showing the box constructed from the blank shown in Figure 1, and with the sections thereof extended.

Figure 5 is a transverse section on the line 5—5 of Figure 4.

Figure 6 is a perspective showing the box 33 in set-up or display position.

Figure 7 is a plan view of Figure 6, and

Figure 8 is a view similar to Figure 7, but showing a modified form of box, and

Figure 9 is a plan view illustrating a further embodiment and showing the containers in dotted lines in folded position upon the intermediate section.

In the embodiment illustrated in the drawings, the box is comprised of three sections, of which *a*, designates the intermediate section, *b*, a side or wing section and *c*, another side or wing section, said sections *b* and *c* being disposed on opposite sides of the intermediate section *a*, and flexibly connected thereto so that the side section *b*, when the parts are disposed, as shown in Figure 4, may be folded upon the intermediate section *a*, after which the side section *c*, is foldable upon the section *b*. The sections *a*, *b* and *c*, conform one with the other in point of size, so that when folded they will appear as shown in Figures 2 and 3. As shown in Figures 2 to 7 the sections *b* and *c*, are constructed so as to provide containers *d* and *e*, which are normally closed except for an opening 5 in the front wall of each, through which the interior of the container is visible. The intermediate section *a*, may be provided with the container *f*, as shown in Figure 8, in which event an opening corresponding to one of the openings 5 would be formed in the front face of the container for the purpose already described in connection with the sections *b* and *c*. The containers *d*, *e*, and *f*, if the latter be employed, are constructed with the view to receive package goods, such as confectionery, the individual packages

being relatively narrow, so that an appreciable quantity may be arranged in each container, and be visible through the opening thereof. It will be noted that a marginal portion 6, surrounds each of the openings 5, as shown in Figure 4, so that surfaces are provided for decorative printing or other advertising matter descriptive of the contents of the containers. Where the intermediate section is constructed, as shown in Figures 4 and 5, the absence therein of an opening, such as designated by 5, in Figures 4 and 5, operates to increase the available

110

space for decorative printing or advertising matter. Section *b*, is flexibly connected at its upper end to section *g*, of a display panel, and section *g*, is flexibly connected 5 to an intermediate section *h*, which is connected to the intermediate section *a*, and to a section *i*, which is flexibly connected to section *c*. As shown by dotted line in Figure 4 the display panel is foldable over the 10 outer or display surface of sections *a*, *b*, and *c*, and the sections thereof are foldable one upon the other in the folding of the sections *a*, *b* and *c*, and when so folded the sections *g*, *h* and *i* are disposed between the sections 15 *b* and *c*. As shown in Figures 4 to 8, inclusive, one side of the section *b*, is directly connected with a side of section *a*, and sections *g* and *h* of the display panel are likewise directly connected together. This 20 structure permits sections *a*, *b*, *g*, and *h*, to fold directly one upon the other. An insert 7, is interposed between the adjacent sides of sections *a*—*c* and *h*—*i*, and approximates in width the depth of one of the 25 containers, and is flexibly connected to the sections *a*—*c* and *h*—*i*, so that a line of folding is provided for sections *c* and *i* in alignment with the outer face of the section *b*, then the same is folded upon section *a*. 30 From the foregoing, it is evident that the sections *a*, *b*, *c*, *g*, *h* and *i*, are foldable into parallel relation with each other, as shown in Figures 2 and 3. When the sections are extended from the position shown in Figure 35 2, to that shown in Figure 4, and parallel one to the other, the display panel may be turned outwardly from the position as shown by dotted line to that shown by full lines in Figure 4. The sections *b* and *c* are then 40 adjusted so as to extend in angular relation to section *a*, whereupon the box is adapted to support itself in upright position, as shown in Figure 6, when arranged upon a suitable surface, such as in a show case 45 or on a counter or shelf or in a show window. This adjustment of the parts will be referred to as the display position, it being obvious that when the parts are arranged, as shown in Figures 6 and 7, so 50 as to face the observer, the contents of the box will be visible through the openings 5 of the containers, together with the advertising matter arranged on the display panel, or on the sections *a*, *b* and *c*, or on both. 55 In the display position of the box, it will be noted that the same is effectively supported against easy toppling, it being evident that each section operates to support the other so there would be required an action 60 on the part of two sections sufficient to move these into parallel relation with the third before lateral falling of the box could occur. This is of importance in that relatively thin or light-weight pasteboard 65 may be employed in the construction of the

box, which would otherwise require the use of relatively heavy stock in order to provide against collapsing thereof in the display position of the parts.

The box thus far described may be formed 70 in any approved manner from one or more blanks of suitable fibrous material, such as pasteboard. A simple and economical structure is shown in Figure 1, which may be readily turned into the forms shown in Figures 2 to 7. From an inspection of Figure 1, it will be noted further that the blank for the forms illustrated by Figures 2 to 7 consists of a single blank of fibrous material such as pasteboard. This blank, which is designated generally by *j*, may be cut from a sheet with a suitable die, or otherwise constructed. The central portion of the blank constitutes the intermediate section *a*, one side of which is joined by the crease-hinge 85 8, to one side of the end section *b*, which is connected by a crease-hinge 9 to a flange 10, comprising one side wall of the container 100 *d*, of Figure 7. A crease-hinge 11 connects the flange 10, with one side of the back wall 13, of the container, the other side of which is connected by a crease-hinge 14 to a flange 15, which forms the opposite side wall of the container, and which is connected by a crease-hinge 16 to a sealing flange 17, which, 90 as shown in Figure 1, is adapted to be secured to the rear face of the front wall *b*, when turned at right angles to the flange 15, and when the latter is turned at right angles to the back 13, and the same turned 95 at right angles to the flange 10, which is also turnable at right angles to the front wall *b*; all of which is shown in Figure 5. A bottom closure flap has a section 18 there- 100 of, which is hinged to the lower end of the front wall *b*, and designed to extend over the space between the front, back and side walls of the container *d* when the same is formed, as shown in Figure 5. A section 19, crease-hinged to section 18, and provided 105 with tabs 20—20, is provided for extending into container *d*, so that the said tabs there- 110 of may interlock with the side walls, the tab 21 of the side wall 15 being provided so as to interlock with the tab 20 in a well-known manner. A top closure flap, consisting of the sections 22, 23 and 24, is provided at the upper end of the back 13 of container *d*, the section 23 being adapted to extend over 115 the space between the side and end walls of the container, and the section 24, being bendable on the crease-hinge 25 and direct- 120 able into the upper end of the container, so as to engage with the tabs 26 and 27, which are disposed inwardly and at right 125 angles to the side walls 10 and 15, to which the said tabs are flexibly connected.

The insert 7 is connected to the side wall of the intermediate section *a*, by a crease- 130 hinge 29, and to the front wall of the sec-

tion *c*, by a crease-hinge 30. The front wall of the container *e*, is also connected by a crease-hinge 31 to a flange 32, which forms a side wall of the container *e*, and which 5 is connected with the back 33 thereof by a crease-hinge 35. A crease-hinge 36 connects back 33 to a flange 37, forming the opposite side wall of container *e*, which is connected by a crease-hinge 38 to the sealing flap 39. 10 A bottom closure flap is made up of the sections 40 and 41, connected together by the crease-hinge 42 and to the back 33 by the crease-hinge 43. A top closure flap, consisting of the sections 44, 45 and 46 is connected to the upper end of the back 33 by 15 crease line 44'. The crease-hinges 47 and 48 connect the sections 44, 45 and 46 together. Suitable tabs 49 are provided on the section 20 41 of the lower closure flap to co-operate with a tab 50 at the lower end of the side wall 37. Tabs 51 and 52 are provided at the upper end of the side walls 32 and 37. In forming the container *e*, the sections 25 thereof, are bent on their respective crease-hinges as described in connection with container *d*. In forming the blank *j*, openings 5—5 of the front walls of sections *b* and *c* are formed, as shown, and a lateral extension is also formed at the intermediate portion of the blank, so as to provide the display panel *K*, the sections *g*, *h*, and *i* of 30 which are connected by the crease hinges 8', 29' and 30', forming continuations of the crease-hinges 8, 29 and 30.

35 With the above construction it will be observed that one face of the blank provides the entire outer surface of the box, when the same is arranged in display position, so that the decorative printing or advertising matter to be arranged on the front or display surface is applied to one face of the blank only, thus reducing the printing to one operation, when the same is done in a single color, and obviating the expensive procedure 40 of printing on two sides of the blank, whether the decorative printing consists of one or more colors. This feature of forming the blank so that one face thereof constitutes the outer face of the sections, *a*, *b*, and *c*, 45 will hold good in the event that the containers *d* and *e* are formed separate from the front walls of sections *a*, *b*, and *c*, and subsequently secured thereto by an adhesive and in a case where three containers are employed as shown in Figure 8.

45 In Figure 9 of the drawings, we have illustrated another alternative form of the device wherein the containers *e'*, *d'* are directly connected to the edges of the intermediate section *a'* by means of crease hinges indicated at 8', the flange 7 above referred to being omitted. The intermediate section *a'* is approximately twice the width of the individual containers. These containers are 50 adapted to be folded inwardly from their

display positions upon one side of the intermediate section *a'*, as seen in dotted line in Figure 9, in which position the containers are disposed side by side in the same plane and substantially entirely cover 70 the surface of the intermediate section *a'*.

It will be understood that the device of this invention may be of any required size, shape, and adapted for use in displaying various kinds of merchandise. In view of 75 this, we reserve the right to incorporate such mechanical changes and modifications within the scope claimed as may be desired, without departing from the spirit or sacrificing any of the advantages of the 80 invention.

We claim:

1. In a display device, a pair of oppositely disposed containers, and an intermediate section hingedly connecting the containers 85 and having a fold line between its hinged side edges to admit folding of the containers in superposed relation upon each other and upon the intermediate section.

2. In a display device oppositely disposed side sections each of which constitutes a container, an intermediate section providing space for a container and having one of its vertically located sides hingedly united to a side of one of said side 95 sections so that the said sections may fold one upon the other, and a flexible connection between the side of the other of said side sections and the opposite side of the intermediate section adapted to permit the 100 last named side section to fold upon the first named side section and a display panel flexibly connected to one of the side sections and adapted to be folded therewith.

3. In a display device oppositely disposed side sections each of which constitutes a container, an intermediate section providing space for a container and having one side thereof hingedly united to a side of one of said side sections so that the said sections may fold one upon the other, and a flexible connection between a side of the other of said side sections and the opposite side of the intermediate section adapted to 105 permit the last named side section to fold upon the first named side section and a display panel connected to one end of the side sections and adapted to be arranged therebetween and foldable therewith.

4. In a display device oppositely disposed side sections each of which constitutes a container, an intermediate section providing space for a container and having one side thereof hingedly united to a side of one of said side sections so that the said sections 110 may fold one upon the other, and a flexible connection between a side of the other of said side sections and the opposite side of the intermediate section adapted to permit the last named side section to fold upon the 115 120 last named side section to fold upon the 125 130

first named side section and a display panel consisting of hingedly united sections flexibly connected to the said side and intermediate sections and adapted to be arranged 5 therebetween and foldable therewith.

5. A display device consisting of a single blank of sheet material having parts adapted to be folded into two opposite marginal containers connected by an intermediate web section, said intermediate web section having a fold line near one side edge, said marginal containers adapted to be folded in superposed relation upon said intermediate section and into compact relation 10 therewith.

6. A display device consisting of a single blank of sheet material having foldable parts adapted to form two separate marginal containers connected to each other by an 15

intermediate web section adapted to carry 20 a centrally located container, said blank being scored at the connections between said web section and the containers to provide hinges permitting said containers to be folded inwardly from their display positions upon the same side of said web section and into compact relation therewith, said intermediate web section having a fold line near one side edge permitting said sections to be folded in superposed relation 25 30 on each other and upon the intermediate web section.

In testimony that we claim the foregoing as our invention, and have signed our names hereunder.

JOSEPH B. SINGER.
ARTHUR B. LEVY.
